(57) **CLAIM**

The ornamental design for a cooking cart, as shown and described.

DESCRIPTION

FIG. 1 is a front, top, and right-side perspective view of a cooking cart, showing my new design;
FIG. 2 is a front view thereof;
FIG. 3 is a back view thereof;
FIG. 4 is a left side view thereof;
FIG. 5 and a right view thereof;
FIG. 6 is a top view thereof;
FIG. 7 is a bottom view thereof;
FIG. 8 is a back, top, and left-side perspective view thereof; and,
FIG. 9 is a partial enlarged perspective view thereof defined by the line-dot-line broken lines circled on FIG. 1.
The evenly spaced broken lines shown in FIGS. 1-8 depict parts of the cooking cart and form no part of the claimed design. The line-dot-line broken lines shown in FIGS. 1 and 9 are used to identify the partial enlarged perspective view and form no part of the claimed design.
